UNITED STATES PATENT OFFICE.

HARVEY E. SHUMWAY AND WALTER T. SCHOLZ, OF FRANKFORT, KANSAS, ASSIGNEES
TO THE S. & S. AUTOMATIC TIREAZE COMPANY, OF MARYSVILLE, KANSAS, A COR-
PORATION OF KANSAS.

VEHICLE-ELEVATOR.

1,144,004.

Specification of Letters Patent. Patented June 22, 1915.

Application filed April 8, 1914. Serial No. 830,439.

To all whom it may concern:

Be it known that we, HARVEY E. SHUM-
WAY and WALTER T. SCHOLZ, both citizens of
the United States, residing at Frankfort, in
5 the county of Marshall and State of Kansas,
have invented certain new and useful Im-
provements in Vehicle-Elevators, of which
the following is a specification.

This invention relates to a vehicle elevat-
10 ing device of that type that has special
utility in its application to the handling of
automobiles, and which automatically lifts
the vehicle to an elevated position so that
the dead weight thereof is removed from
15 the tires when not in service.

The object of the invention is to provide
a simple and substantial device of the char-
acter set forth which will automatically con-
vert the forward motion of the vehicle into
20 upward motion which will raise the same so
that the wheels are out of contact with the
ground, in a manner similar to our pending
applications Serial Nos. 785,586, filed Au-
25 gust 19, 1913, and 821,013, filed February
25, 1914. In addition to automatically rais-
ing the vehicle from the ground, the present
device includes means for automatically re-
taining the vehicle in its raised position,
30 which is also capable of elevating the ve-
hicle to a still higher position than that at-
tained by the original momentum thereof.

The invention also contemplates the pro-
vision of novel means for starting the rise
35 of the vehicle platform. That is to say, to
insure the full coöperation of the several
elevating parts to the best advantage, the
present construction has in view a prelimi-
nary lifting device which materially aids
40 and facilitates the operation of the appa-
ratus.

With the above and other objects in view
which will more readily appear as the na-
ture of the invention is better understood,
45 the same consists in the novel construction,
combination and arrangement of parts
hereinafter more fully described, illustrated
and claimed.

A preferred and practical embodiment of
the invention is illustrated in the accom-
50 panying drawings, in which—

Figure 1 is a side elevation of the appa-
ratus in its folded or collapsed position.
Fig. 2 is a side elevation showing the ve-
hicle platform elevated to a horizontal
55 plane. Fig. 3 is a top plan view of the

construction shown in Fig. 2. Fig. 4 is a
transverse sectional view on the line 4—4
of Fig. 3. Fig. 5 is a transverse sectional
view on the line 5—5 of Fig. 3.

Similar reference characters designate 60
corresponding parts throughout the sev-
eral figures of the drawings.

The present embodiment includes in its
organization a plurality of inclined elevat-
ing guides 1—1 and 2—2, which are prefer-
ably arranged in pairs to form front and
rear sets of prime elevating members A and
B. At this point, it may be noted that each
of the guide members 1—1 comprising the
front set A are of similar construction while 70
the guide members 2—2 of the rear set B
are also similar to each other. That is, to
say, each of the members 1—1 which are of
substantially I-beam formation includes a
guide channel 3 which is formed by the side 75
walls 4 and 5. The side wall 5 which is the
outer one of the walls of the channel is pro-
vided with an inturned holding flange 6 at
its top edge. This construction is also com-
mon to the guide members 2—2, so that the 80
only substantial difference between the mem-
bers forming the front and rear sets of ele-
vating guides A and B is in the length and
shape of the guide channels which in the
members 1—1 are curved at their upper 85
end as at 7 to act as a shock absorber should
the momentum of the vehicle tend to carry
the vehicle supporting platform 8 farther
forward than necessary to cause the tires
of the vehicle to clear the floor. 90

The vehicle supporting platform 8 com-
prises a pair of parallel frame bars 9 which
are connected by transverse braces 10 and
11. In connection with the braces 10 at the
forward end of the platform, it will be ob- 95
served that the same comprises for con-
venience in assembling duplicate sections 12
and 13 each of which have overlapping
tongue portions 14 which may be fastened
together by the bolts 15 as shown in Fig. 4. 100
Each of the frame bars 9 is provided at
its forward end with a vehicle abutment 16,
and its rear end with a rear axle engaging
socket member 17. With further reference
to the vehicle abutment 16 it will be ob- 105
served that the same is provided with a piv-
oted latch member 16^a which is substan-
tially arc-shaped and normally has one end
thereof below the other as shown in Fig. 1.
The object of this construction is to enable 110

automobiles whose steering rods are in front of the front axle to operate the device without injury to the said rod. In other words by this arrangement when a car having the rods in front is guided on the platform the rod will strike the lower ends of the latches 16^a and cause their forward ends to dip forward between the axle and steering rod, that is, to the position shown in Fig. 2 and 10 form a bumper for the axle itself.

By reference to Fig. 1, it will be observed that the platform 8 is normally in an inclined position, so that the first movement thereof caused by an oncoming vehicle is 15 from this position to a horizontal plane as shown in Fig. 2. In order to effect this action of the platform, each one of the frame bars comprising the same is provided at its forward end with the fixed supporting 20 arms 18 which are rigidly secured to the frame bars 9 and front brace 10, while the rear ends of said bars have pivotally attached thereto suitable elevating links 19. These said links 19 may be 25 lengthened if desired to cause the rear end of the platform to be raised higher than the front as in our other pending applications herein mentioned. The elevation of the rear end of the platform to a greater 30 height than the front may also be accomplished by increasing the angle of the rear inclines 5. Since the change of pitch of the inclines 5 and the length of the links 19 are merely matters of degree, the same are not 35 shown on the drawings, though it will of course be understood that these changes can be resorted to without departing from the invention, to accommodate the present device to the particular type of car with which 40 it is used. Each of the supporting arms 18 and the pivoted elevating links 19 have attached to their lower ends wheeled trucks 20 which are adapted to travel in the channels 3 of the inclined guide members 1—1 45 and 2—2.

As will be observed from Fig. 1, the purpose of pivoting the elevating links 19 is to permit the device to assume a folded or collapsed position, so that a vehicle being 50 driven astride the platform will have no hindrance until it strikes the abutments 16. Each of the elevating links 19 have at their lower ends which are also pivoted in the trucks 20, a trip notch 21 which is adapted 55 to engage with an upstanding stud 22 in the channel or guide of the members of the rear set of prime elevating guides B. The location of this stop projection 22 is such that it will come in contact with the 60 wall 23 of the notch 21 during the forward movement of the platform 8 thereby tilting the links 19 from their rearwardly inclined position to a perpendicular position as shown in Fig. 2. In order to prevent the links 19 65 from tilting forward out of their perpendicu-

lar plane each of the frame bars 9 carries a stop member 24 directly behind the pivot point of each link. It will thus be observed that as soon as a vehicle strikes the abutments 16 on the front of the platform 8, the latter will be lifted to a horizontal position 70 because of the links 19 being thrown into the position shown in Fig. 2, and the trucks 20 at the ends of the supporting members 18 and 19 will ride up the inclined channels 75 of the guide members as far as the momentum of the machine will carry the same. Further, in connection with the notch 21, it will be observed that upon the descent of the platform 8 from its elevated position to 80 its normal collapsed position, the wall 25 of said notch will engage with the stop projection 22 to tilt the links 19 from their perpendicular or vertical position back to their original rearward inclination. 85

For the purpose of rendering the operation of the apparatus more efficient and giving the links 21 their initial tilt or movement, each of the frame bars 9 carries at its extreme rear end a depending bracket arm 90 26 in which is journaled a roller 27 which rides upon the face 28 of a starting cam 29. One of these starting cams 29 is arranged in line with and to the rear of each of the guide members 2—2, so that it is apparent 95 that upon any forward movement of the platform 8 a quick upward movement of the rear end of the platform will be effected to cause the sockets 17 to quickly and positively engage the rear axles of the machine. 100

For the purpose of retaining the platform 8 in its elevated position, or elevating it to a higher position than that attained by the original momentum of the vehicle, the front end of the apparatus is provided with an 105 auxiliary elevating and retaining device designated in its entirety by the reference character C. This portion of the device essentially comprises a rack member 30 which has pivotally attached to the rear end thereof 110 the bracket arms 31 which connect with the transverse front brace 10 between the frame bars 9 of the vehicle platform. The rack 30 is longitudinally movable in a guide housing 32 and meshes with a pinion 33 journaled 115 upon a shaft 34 which latter is supported in a suitable frame work 35 arranged transversely of the apparatus between the front guide members 1—1. The pinion 33 has connected therewith a ratchet wheel 36 that 120 is engaged by a spring pressed pawl 37 pivoted to a portion of the frame work 35. A rocking lever 38 is pivoted on the shaft 34 adjacent the ratchet wheel 36 and is also provided with a spring pressed pawl 39 125 adapted to engage with the teeth of the ratchet in such a manner that upon each forward movement of the lever, the pinion will be rotated to draw the rack 30 forward thereby causing the platform 8 to be elevated 130

to a higher position, because of the connection between the end of the rack and the brace 10 of the platform.

From the foregoing description, the operation of the device is believed to be apparent. However, in order to sum up the general action thereof, it will be observed from Fig. 1 which shows the normal collapsed position of the apparatus, that the 10 elevating platform 8 is inclined so that its rear end is low enough to provide clearance for an oncoming vehicle, so that no part of the latter comes in contact with any part of the apparatus until it reaches the abutments 15 16. Immediately upon contact with the said abutments, the vehicle pushes the platform 8 forward, the rear end thereof being quickly elevated so that the entire platform assumes a horizontal position and the sockets 17 are 20 thrown into engagement with the rear axle of the vehicle. By providing the starting cam 29 at the rear end of the device, it will be obvious that the action of this part of the apparatus is materially hastened while at 25 the same time considerable strain is relieved from the links 19 before they come in contact with the trip or stop stud 22. If the momentum of the vehicle causes the apparatus to assume the position shown in Fig. 2, 30 and it is desired to elevate the same still higher, it is only necessary to bring into action the auxiliary elevating and retaining mechanism C. That is to say, by rocking the lever 38, the ratchet wheel 36 which is 35 keyed to the pinion 33 is rotated so that the said pinion 33 pulls the rack 30 forward, thereby pulling the platform 8 forward also in such a manner that the trucks 20 are forced to climb higher in the channels of the 40 guide members. In order to bring the platform 8 to its normal position and effect the collapse of the apparatus, it is only necessary to disengage the pawls 37 and 39 from the ratchet 36, and the weight of the vehicle will 45 quickly cause the several parts to assume their normal position.

We claim:

1. A vehicle elevating device including a plurality of stationary guide members, and 50 a vehicle supporting platform having relatively fixed truck members slidably mounted in certain of said guide members and also having automatically foldable truck members slidably mounted in other of said guide members.

2. A vehicle elevating device including front and rear pairs of stationary inclined guide members, and a vehicle supporting platform carrying fixed truck members riding on the front guides, and also carrying folding rear truck members riding on the rear guide members.

3. A vehicle elevator including a vehicle supporting platform, a plurality of inclined 65 guide members, supporting members carried

by the platform and riding in said guide members to elevate the platform, and means for elevating and retaining the platform to higher elevated positions.

4. A vehicle elevator including a vehicle 70 supporting platform, a plurality of inclined guide members, said vehicle platform carrying supporting members riding in said guide members to elevate the same, cam means for starting the rise of the platform and means 75 for holding the platform in elevated position.

5. A vehicle elevator including a vehicle supporting platform, a front and rear set 80 of inclined guide members, supporting members rigidly carried by the front end of said vehicle platform, and other supporting members pivotally carried by the rear of said platform, each of said supporting members adapted to ride in the inclined elevat- 85 ing guide members, and means for elevating and retaining the platform in higher elevated positions.

6. A vehicle elevator including a vehicle supporting platform, a front and rear set 90 of inclined guide members, supporting members rigidly carried by the front end of said platform, and other supporting members pivotally carried by the rear of said platform, each of said supporting members 95 adapted to ride in the inclined elevating guide members, cam means for starting the rise of the rear end of the platform, and auxiliary elevating and retaining means connected to the forward end of said platform. 100

7. A vehicle elevating device including a vehicle platform and a plurality of inclined elevating guides, supporting trucks carried by said platform and movable in said guides, cam means for starting the rise of 105 the said platform, and auxiliary elevating and retaining means connected with the forward end of said platform.

8. A vehicle elevating device including a vehicle platform and front and rear sets of 110 inclined elevating guides, rigid supporting arms carried by the front end of said platform and movable in the front inclined elevating guides, pivoted elevating and supporting links carried by the rear of the 115 vehicle platform and movable in the rear inclined elevating guides, means for tripping the rear supporting members to their extended position, and auxiliary elevating and retaining means connected with the forward end of said platform. 120

9. A vehicle elevating device including a vehicle platform and front and rear sets of inclined elevating guides, fixed means carried by the front of said platform adapted 125 to ride in the front set of inclined elevating guides, pivoted elevating means carried by the rear of said platform and adapted to ride in the rear set of inclined elevating guides, cam means for starting the rise of 130

the rear end of the platform, means for tripping said pivoted elevating means to abruptly raise the rear end of the platform to its horizontal position, and auxiliary elevating and retaining means connected with the forward end of said platform.

10. A vehicle elevating device comprising a vehicle platform normally lower at its rear end than at its front end, front and 19 rear sets of inclined elevating guides, fixed supporting members carried by the platform and movable in the front set of inclined elevating guides, supporting links carried by the rear of the platform having one end 15 pivoted thereto and the other pivoted in a truck movable in the rear inclined elevating guides, means for tripping said supporting links to raise the rear end of the vehicle platform to the same level as the front end, 20 and auxiliary elevating and retaining means connected with the forward end of said platform:

11. A vehicle elevating device comprising a vehicle platform normally lower at its 25 rear end than at its front end, front and rear sets of inclined elevating guides, fixed supporting members carried by the platform and movable in the front set of inclined elevating guides, supporting links carried by the rear of the platform having one end 30 pivoted thereto and the other pivoted in a truck movable in the rear inclined elevating guides, cam means for starting the rise of the rear end of the platform, means for

tripping said supporting links and coöperating with said cam means to raise the rear end of the vehicle platform to the same level as the front end, and auxiliary elevating and retaining means connected with the forward end of said platform. 35

12. A vehicle elevating device including a vehicle platform normally lower at its rear end than at its front end, front and rear sets of inclined elevating guides, fixed supporting members carried by the front end 45 of said elevating platform, trucks pivotally receiving the lower end of said fixed supporting members and movable in the front set of inclined guides, supporting links pivotally carried by the rear of said platform 50 and provided with a trip notch, trucks pivotally receiving the lower ends of said supporting links and movable in the rear set of inclined guides, stop projections located in the rear guides and adapted to engage 55 with the trip notches of the supporting links to tilt the latter, cam means for starting the rise of the vehicle platform, and auxiliary elevating and retaining means connected with the forward end of said platform. 60

In testimony whereof we hereunto affix our signatures in the presence of two witnesses.
